UNITED STATES PATENT OFFICE.

VERNON A. NEWPORT, OF DAYTON, PENNSYLVANIA.

RAILROAD-JOINT.

1,270,968.

Specification of Letters Patent.

Patented July 2, 1918.

Application filed January 25, 1918. Serial No. 213,779.

To all whom it may concern:

Be it known that I, VERNON A. NEWPORT, a citizen of the United States, residing at Dayton, in the county of Armstrong and 5 State of Pennsylvania, have invented certain new and useful Improvements in Railroad-Joints, of which the following is a specification.

This invention is a rail joint and has 10 special reference to a rail chair.

One object of this invention is the production of a rail joint which obviates the necessity of fish plates as the clamping frames support the rails and at the same 15 time hold the ends of the rails in correct alignment.

Another object of this invention is the production of a rail joint which is formed of a pair of similarly constructed clamping 20 sections which are arranged to fit upon the abutting ends of two rails for constituting a support, which will positively hold the ends of the rails in alignment and will reduce the vibrations of trains passing over 25 the rail joint.

Another object of this invention is the production of a rail joint wherein each clamping section comprises a central receiving web having diverging brace portions extending upwardly therefrom while a gripping bar is secured intermediate its ends to a web and contiguous its ends to the brace portions, whereby the device being formed as a one-piece structure will constitute a 35 firm support for the abutting ends of two rails.

With these and other objects in view, this invention consists of certain novel combinations, constructions, and arrangement of 40 parts as will be hereinafter fully described and claimed.

One practical form of construction and assembly of the present invention will be hereinafter described and is illustrated in 45 the accompanying drawing, in which—

Figure 1 is a top plan view of the rail joint illustrating the same in use.

Fig. 2 is a side elevation of the invention, the metallic supporting tie being shown in 50 section.

Fig. 3 is a transverse section through the device.

Fig. 4 is a section taken on the line 4—4 of Fig. 2.

55 Referring to the accompanying drawing by numerals, it will be seen that the two

clamping sections are similarly constructed and for this reason it is thought that a description of one section will be sufficient to disclose the construction of both.

Each section comprises therefore, the elongated flat bar 5 having spaced depending extensions 6 connected at their lower ends by the thickened bridge 7. Thus it will be seen that the central portion of the bar 5 together with the extensions 6 and the bridge 7 constitute a substantially rectangular web.

The diverging brace portions 8 extend from the end of the bridge 7 upwardly to 70 have their ends upon the bar 5 adjacent the ends thereof, as illustrated in Fig. 1.

The clamping section is formed of a one-piece structure, as it is cast or may be formed from a blank.

When this rail joint is in use, a pair of clamping sections are employed and it is of course obvious that the device is to be used in connection with any form of the tie desired, although it is illustrated in the accompanying drawing as being used in connection with a metallic tie 9. The abutting ends of two rails 10 are positioned upon the tie 9 and as shown the clamping sections of the joints are positioned upon the abutting 85 ends of the rails. The clamping sections are positioned so as to cause the tie to be passed through the rectangular web portions and owing to the rectangular construction of these web portions, it is obvious that the 90 clamping section will be firmly held upon the tie and any tendency of wobbling will be resisted.

It is intended to have the bars of such length as to project for considerable distance beyond the ends of the rails for reinforcing the joint of the same. It is obvious the bracing portions will reinforce the bars adjacent their ends.

The bolts 11 may be passed through spacing sleeves 12 interposed between the clamping sections and these bolts 11 may receive nuts 13 upon their projecting ends.

By referring particularly to Fig. 2, it will be seen that the bolts project through the junction of the bars and the extensions 6 and the bracing portions 8, as well as through the junction of the bracing portions and the bridge. By interposing the spacing sleeves between the clamping sections and by screwing the nuts onto the bolts, it is obvious the clamping 105 sections will be firmly clamped upon the rails.

110

It will also be noted that if so desired vertical bolts 14 may be passed through the bars 5 at points adjacent the center thereof and may also be passed through the base of 5 the rails and through the tie for receiving nuts 15, thus holding the tie against shifting with respect to the abutting ends of the rails.

By referring particularly to Fig. 4, it 10 will be seen that the bars 5 are provided with underlapping lugs 16. These lugs 16 are formed to extend in substantially horizontal planes and in alinement with each other, thus fitting under the base of the rail for 15 reinforcing or steadyng the rail joint at its end. Since the rail joint is formed of similarly constructed sections secured together, as these sections may be either cast or formed from blanks, it is obvious the lugs will 20 firmly engage the base of the rail when the device is being assembled and afterward when the same is in use.

Upon referring to Figs. 1, 2 and 3, it will be seen that the extensions 6 and the brace 25 portions 8 extend downwardly in alinement with the outer portions of the flat bars 5 of the sections. Therefore, when the metallic supporting tie 9 has been inserted through the web of each section, it is obvious the ends 30 of the rail will bear directly upon this tie. Furthermore, particular attention is invited to the fact that the web and braces of these sections are spaced apart for the same distance as the breadth of the bases of the abutting 35 ends of the rails. Therefore, the steady pull upon the rails by the sections of the clamp will be such as to hold the rails against any tendency of tipping over when strain is brought to bear in a lateral direction upon 40 these rails. The sections are spaced apart for the same distance as the breadth of the base of each section, as hereinbefore specified and thus the increased leverage for each section will permit the sections to hold the 45 rails against tipping over, which would not be the case if the sections were lapped around under the base of the rails and then held very close to each other throughout their entire length. Furthermore, it will be seen 50 that the spacing collars of the bolts will hold the lower portions of the sections spaced from each other, although the sections will be firmly clamped upon the base of each rail, thus causing the increased leverage 55 to positively hold the rails against shifting, as hereinbefore specified.

From the foregoing description, it will be seen that a very strong clamp has been produced which will firmly reinforce the abutting 60 ends of two rails and will thus reduce the vibration of trains passing over these

abutting ends, while owing to the simplicity of the structure, the rail joint may be manufactured at a minimum cost and may be easily applied to the rails.

65

As only one form of the invention has been described and illustrated, it is obvious that many changes may be made in the detail construction of the present invention, as long as these changes do not exceed the scope 70 of the device as claimed.

What is claimed is:—

1. In a rail joint of the class described, the combination of a plurality of similarly constructed sections, each section comprising an 75 elongated flat bar having gripping portions thereon to fit around the base of a rail, and depending portions extending from the outer edges of said flat bar, thus causing said depending portions to be in parallel planes extending across the outer edges of the base of a rail, to allow said depending portions to be spaced apart for the same distance as the breadth of the base of a rail, thus permitting the depending portions to be fitted over 80 a supporting element to hold the ends of the abutting rails in alinement and exert pulls upon the ends of said rails at the edges of the bases thereof, thus preventing the rails from tipping over when strain is brought to 85 bear thereon.

2. In a rail joint of the class described, the combination of a pair of similarly constructed sections, each section comprising an elongated flat bar, depending extensions projecting from said bar adjacent its outer edge, braces extending from the ends of said bar adjacent its outer edge and being connected to the lower portions of said extensions, a bridge connecting the lower portions of said extensions, thus causing said extensions, said braces and said bridge to be in alinement with the outer edge of said bar, lugs formed on the outer edge of said bar and extending inwardly therefrom, thus causing the bar to fit upon the base of a rail, whereby when said sections are in use, said extensions, braces and bridges will extend parallel in planes extending along the side edges of the base of a rail, whereby when a supporting tie is interposed between said extensions and said bridges, said sections will pull upon the tie in direct alinement with the edges of the base of the rail, thus presenting an increased leverage for the sections for preventing the 105 rail from tipping over.

In testimony whereof I affix my signature in presence of two witnesses.

VERNON A. NEWPORT.
